PLANAR TUBE

David R. Weindorf, Santa Monica, Calif., assignor to Sylvania Electric Products Inc., a corporation of Massachusetts

Application May 27, 1955, Serial No. 511,531

10 Claims. (Cl. 313—257)

This invention relates to electron discharge tubes, and more particularly to an improved construction of the type known as planar tubes, and the method of making tubes of this type.

In conventional planar tubes, the grid or grids and the anode of the tube are mounted within a glass envelope by means of support rods extending from a glass base, and are positioned with respect to one another by ceramic spacers. The glass envelope is hermetically sealed to the glass base, thus providing for a vacuum tight enclosure.

Another known construction of a planar tube utilizes a glass base, and a glass envelope, the walls of which have hermetically sealed therein the support elements for the tube electrodes. These electrodes are spaced from one another and held in position by the glass envelope wall.

These conventional planar tube structures are difficult to fabricate and therefore expensive to produce. The difficulties arise primarily from the inherent fragility of glass and the numerous glass to metal seals which are required, since it is often necessary, in a multi-element tube, that a number of seals be made independent of one another and at closely spaced positions. The heat necessary to provide for a satisfactory seal at one position affects adjacent seals, and produces undesirable strains in the surrounding glass. These difficulties are highly magnified in present day electron tube constructions, since the tendency is in the direction of decreasing the dimensions of the tube. It is not uncommon to produce planar tubes having overall dimensions no larger than one-half an inch. Therefore, the heat needed to produce any of the seals, even though the heat source is highly concentrated, cannot be so restricted to an area so as not to affect adjacent seals.

Resolving the aforementioned difficulties, it is apparent that a desirable structure for a stacked tube would comprise elements which are physically rugged and compact, are made of similar materials which are inherently dimensionally stable under high temperatures, and are of configuration requiring a minimum number of sealing operations. In addition, these structures must be adaptable to efficient automatic production methods.

The present invention provides for a planar tube which has the aforementioned advantages. Accordingly, an object of this invention is to provide for a planar tube which is small, compact, and rugged.

Another object of this invention is the provision of an electron discharge device adaptable for automatic production.

A further object of this invention is the utilization of ceramic materials for tube elements and which are not affected by heat to an undesirable extent, some of these ceramic materials having the function of forming part of the enclosure for the electrode elements.

A still further object of the invention is the provision of a planar electron tube wherein the spacer elements for

2

the electrodes of the tube have co-extensive outside surfaces, and a common seal.

A still further object of the invention is to provide a method of making a planar electron tube wherein a minimum number of sealing operations produces a completed vacuum tight enclosure.

The foregoing objects, as well as additional objects, which will be apparent after reading the following description, are attained by the provision of an electron discharge tube which employs ceramics for support structures and spacers rather than glass, since ceramics are inherently dimensionally stable under the high temperatures needed to produce adequate hermetic seals between the various elements during the process of constructing the tube.

15 The novel structure of the present invention utilizes essentially a cathode mounted upon an anode ceramic spacer, and a grid electrode positioned intermediate the cathode and anode by means of the ceramic base member and a ceramic grid spacer. These elements are circular in shape and have equal diameter so that their outside surfaces are co-extensive. A single seal hermetically encloses the base member, grid electrode, grid spacer, and anode spacer along the co-extensive surface. Surrounding the seal is a metal sleeve which serves as a securing device for these 20 elements in addition to providing for an external grid connection. The final seal of the anode to the anode spacer is made by an anode conductor plate, and in one embodiment of the invention, an exhaust tubulation. The parts constituting the electron discharge tubes are stacked 25 upon one another in proper sequence, the sealing mediums are positioned adjacent the parts to be sealed, and the assembly is heated to fuse the sealing medium. The assembly is subsequently evacuated.

The present invention will be more fully understood by 30 reference to the following detailed description taken in conjunction with the accompanying drawings in which

Fig. 1 is a view in section of one embodiment of the planar electron tube constituting the invention.

Fig. 2 is a section through Fig. 1 on the line 2—2, and 35 Fig. 3 is a view in section of another embodiment of the planar tube constituting the invention.

Referring to Fig. 1, a base member 11 of ceramic such as Zircon Porcelain, has mounted thereon a filamentary cathode 13. The base member comprises a cylindrical wall 15 and an internal platform 17 having a central depression 19 and an annular rim 21. The platform is spaced from the wall 15 at its upper portion by channel 23 and is integral with the wall at its lower portion. Filamentary cathode 13 is bridged across rim 21, with 50 both of its ends extending into channel 23. One end of the cathode is attached to filament lead 27 by means of tab 25 and connectors 29. The other end of the cathode is connected to filament lead 27 by means of tensioning device 31. These cathode connections may be made in any suitable manner, such as by welding. The filament leads 27 extend through the base member 11, thereby providing for the external filament electrical connections.

A circular metallic grid disc or annulus 33 having grid wires 35 mounted thereon, is flush with the end of cylindrical wall 15 and overlies the opening in channel 23. The grid annulus has an inside diameter greater than the diameter of platform 17, thereby providing a space through which the cathode may pass. Abutting the planar surface of grid disc 33, opposite base member 11, is a metallic grid spacer 37, whose outside diameter is equal to the outside diameter of the grid disc. The surface of grid spacer 37 opposite the grid disc abuts an annular anode spacer 39 of a ceramic material, such as Zircon Porcelain. The outside diameter of the anode being L-shaped in cross-section. The outside diameter of the horizontal section spacer is equal to the outside diameter of the grid spacer 37. Therefore, the outside sur-

60 65 70

faces of base member 11, grid disc 33, grid spacer 37, and anode spacer 39 define a cylindrical co-extensive surface. A metallic anode connector plate 41 is positioned against the end of the vertical section of spacer 39 and may be attached to a metallic exhaust tubulation 43 by a brazed on retaining ring 44. Preferably, ring 44 is a split ring of tungsten wire which is forced over the exhaust tubulation and holds plate 41 in place by virtue of its spring action on the exhaust tubulation 43. Connected to the lower open end of tubulation 43 is the metallic anode disc 45. Near the center of the anode is a port 47 providing an opening through which the assembled tube may be evacuated. The anode is positioned with respect to the grid wires 35 by means of its abutting relationship with the bottom surface of the inner portions of the horizontal section of anode spacer 39, and by virtue of the position of grid spacer 37. The anode is attached to tubulation 43 in any conventional manner, such as by soldering, brazing or welding. A metal sleeve 49 surrounds the adjacent co-extensive surfaces of base member 11, grid disc 33, grid spacer 37, and anode spacer 39. The sleeve has a shoulder 51 abutting the outside upper surface of the horizontal section of anode spacer 39.

A getter bar 53 is mounted upon a tab 55 and getter lead 57, which also provides one electrical connection for the getter. A cut-out portion 56 in the rim 21 provides for passage of the getter bar across the depression 19. Fig. 2 illustrates the position of the getter bar with respect to the filament 13. The getter flash is directed downwardly into the depression 19, and away from the filament. The end of the getter bar opposite tab 55 is connected to getter tab 58, which extends across channel 23 and contacts the under side of grid disc 33. This contact provides the second electrical connection for the getter.

The filament leads 27 are hermetically sealed to base member 11 by a solder ring sealing medium 59 such as a high purity lead confined within the walls of cylinders 60. Exhaust tubulation 43 is hermetically sealed to anode spacer 39 by a similar sealing medium 61, and the co-extensive surfaces of base member 11, grid disc 33, grid spacer 37, and anode spacer 39 are also hermetically sealed with one another by a high purity lead sealing medium 63.

The electrical leads for filament 13 are provided by leads 27. The grid connection and one getter connection is made by means of grid disc 33, lead solder 63, and sleeve 49. The second connection for the getter is provided by lead 57. The anode connection is made by the metal exhaust tubulation 43 and anode connector plate 41.

Fig. 3 shows another embodiment of a planar electron tube wherein a ceramic base member 64 has a filament 65 mounted thereon by means of a tab 67 on one end and a tensioning device 69 on the other. The filament connections are made by leads 71. A grid disc 73 is positioned between the base member 64 and a grid spacer 75, this spacer abutting an anode spacer 77 on the surface opposite the grid disc 73. The outside diameters of the base member, grid disc, grid spacer, and anode spacer are equal, thereby forming a co-extensive surface. They are surrounded by metallic sleeve 79, which also serves as the electrical connection for the grid. Between the sleeve and the co-extensive surface is a high purity lead hermetic sealing medium 81. The sealing medium 83 for the filament leads has the same type of sealing composition as above.

A cup-shaped metallic anode support 80 positions the anode 82 by means of a connection between the base 84 of the cup and the anode, and by means of the lip 85 of the cup cooperating with anode spacer 77. The connection between the base of the cup and the anode may be made in any convenient manner, such as by welding or soldering. The cup-shaped anode support 80 has an aperture 87 in the central region of base 84 to facil-

tate exhausting the electron tube assembly through an aperture 89 in the anode. An anode contact plate 91 is attached to lip 85 of anode support 80 by means of solder ring 93. On the inner surface of the contact plate is embedded a getter 95. Sealing mediums 81, 83, and 86 support and hermetically seal the metallic and ceramic elements associated therewith. Sealing medium 81 traverses the co-extensive surface formed by base member 64, grid disc 73, grid spacer 75 and anode spacer 77.

Referring to the planar tube shown in Fig. 1, the method of assembling the elements of the tube is as follows. The ceramic base member 11 and anode spacer 39 are painted or otherwise coated with a wetting agent such as a suspension of titanium hydride in a nitrocellulose lacquer. A cathode sub-assembly is formed by welding cathode 13 to tensioning device 31 on one end and connector 29 on the other. Cylinders 60 are slipped over the filament leads 27, and a high purity lead sealing ring is positioned within the cylinders and adjacent the leads. The getter tab 55 is welded to getter lead 57.

An anode sub-assembly is constructed by welding anode plate 45 to the tubulation 43 and threading tubulation 43 through the aperture in anode spacer 39 until the plate engages anode spacer 39; then the high purity lead sealing ring 61 is placed between the anode spacer and exhaust tubulation, and plate 41 is attached to the tubulation by means of a ring 44.

The sub-assemblies and other elements of the tube are then assembled in a suitable holding device or jig so that the exhaust tubulation is in a downward position. The anode sub-assembly is threaded through the aperture in sleeve 49 and is positioned with the anode spacer abutting shoulder 51. Grid spacer 37, grid disc 33, and the cathode sub-assembly is stacked upon the anode sub-assembly, and a high purity lead solder ring is placed within the confines of sleeve 49. The free end 58 of getter bar 53 is slipped between grid disc 33 and base member 11. The final step in the assembly process is the fusing and hermetic sealing operation wherein the parts are rigidly affixed to one another. The entire tube is heated in a vacuum or in a chamber provided with a non-oxidizing gas such as argon or hydrogen to a temperature of approximately 800° centigrade by any suitable means, such as an induction coil, whereat the titanium hydride decomposes and the lead sealing mediums 59, 61, and 63 wet the ceramic whereby fusion between the sealing medium and the metallic elements associated therewith occurs. After assembly the tube can be processed and evacuated in a conventional manner.

The cathode sub-assembly of the planar tube shown in Fig. 3 is made in the same manner as described for the embodiment shown in Fig. 1. The anode sub-assembly is constructed by placing support cup 80 within the aperture in anode spacer 77, slipping a sealing ring 86 between the cup and anode spacer walls, and welding anode 82 to the base of the cup. The anode spacer is thereby confined between lip 85 and anode 82.

The sub-assemblies and other elements of the tube are assembled in an inverted position. The anode sub-assembly is threaded through the aperture in sleeve 81 and rests upon the sleeve shoulder and upon solder ring 93 and getter plate 91. Grid spacer 75, grid disc 73, and the cathode sub-assembly is then stacked upon the anode 82 sub-assembly in sequence. A high purity lead sealing ring is then positioned within the confines of sleeve 81. This assembly is placed within a vacuum bell-jar, and after evacuation, the entire tube is heated to cause a simultaneous fusion of sealing medium 81, 83, and 86 with their associated metallic and ceramic elements. A concentrated radio frequency coil fuses solder 93 with getter plate 91 and cup 80, and also flashes getter 95 to complete the operation.

It is apparent from the foregoing, that the planar tubes described herein are ruggedly constructed and adaptable

for automatic production. The co-extensive peripheral surface defined by the base member, grid disc, and grid and anode spacers provide a simple and effective means whereby these elements may be rigidly affixed and hermetically sealed to one another. In addition, the heating operations required to completely fuse and seal the structures into a unitary assembly are performed in such a manner that none of the previously made connections are adversely affected by the operation. Also, the use of Zircon Porcelain ceramic, titanium hydride, and a high purity lead solder provides an efficient and effective means for attaching, positioning, and sealing the electrodes with one another, and alleviates the serious glass strain difficulty previously experienced when several independent glass to metal seals had to be made by the application of heat at closely spaced positions. However, these material compositions were only recited as examples. Although several embodiments of the invention have been shown and several methods of assembly described, it is to be understood that other modifications will be obvious to one skilled in the art, and that these modifications are within the scope of the invention.

What is claimed is:

1. An electron discharge device including a cathode mounted upon a base member, and an anode mounted upon an anode spacer, said member and anode spacer having co-extensive outside surfaces and a common hermetic seal for said member and spacer, said seal being in contact with said coextensive outside surfaces and spanning the juncture between said member and spacer.

2. An electron discharge device including a cathode mounted upon a ceramic base member, and an anode mounted upon an anode ceramic spacer, said base member and anode spacer having co-extensive outside surfaces and a common hermetic seal for said member and spacer, said seal being in contact with said coextensive outside surfaces and spanning the juncture between said member and spacer.

3. An electron discharge device including a zircon base member having a cathode mounted thereon, and an anode mounted upon a zircon anode spacer, said base member and anode spacer having co-extensive outside surfaces and a common hermetic seal for said member and spacer, said seal being in contact with said coextensive outside surfaces and spanning the juncture between said member and spacer, said seal being of a composition comprising a high purity lead solder.

4. An electron discharge device including a base member having a cathode mounted thereon, an anode spacer, an anode mounted upon said spacer, at least one grid electrode, and at least one grid spacer, said grid electrode being positioned intermediate the cathode and anode by means of said base member and the grid spacer, said base member, grid electrode, grid spacer, and anode spacer all having a common hermetic seal, said seal comprising a single band of sealing material surrounding and bonded to peripheral surfaces of said members, electrode and spacers.

5. An electron discharge device including a ceramic base member having a cathode mounted thereon, a ceramic anode spacer, an anode mounted upon said spacer, at least one grid electrode, and at least one grid spacer, said grid electrode being positioned intermediate the cathode and anode by means of said base member and the grid spacer, said base member, grid electrode, grid spacer, and anode spacer all having a common hermetic seal, said seal comprising a single band of sealing material surrounding and bonded to peripheral surfaces of said members, electrode and spacers.

6. An electron discharge device including a base member having a cathode mounted thereon, an anode spacer, an anode mounted upon said spacer, at least one grid electrode, and at least one grid spacer, said grid electrode

being positioned intermediate the cathode and anode by means of said base member and the grid spacer, said base member, grid electrode, grid spacer, and anode spacer all having co-extensive outside surfaces and a common hermetic seal, said seal comprising a single band of sealing material surrounding and bonded to peripheral surfaces of said members, electrode and spacers.

7. An electron discharge device including a base member having a cathode mounted thereon, an anode spacer, an anode mounted upon said spacer, at least one grid electrode, and at least one grid spacer, said grid electrode being positioned intermediate the cathode and anode by means of said base member and the grid spacer, said base member, grid electrode, grid spacer, and an anode spacer all having circular co-extensive outside surfaces and a common hermetic seal, said seal comprising a single band of sealing material surrounding and bonded to peripheral surfaces of said members, electrode and spacers.

8. An electron discharge device including a base member having a cathode mounted thereon, an anode spacer, an anode mounted upon said spacer, at least one grid electrode, at least one grid spacer, and a metal sleeve, said grid electrode being positioned intermediate the cathode and anode by means of said base member and the grid spacer, said base member, grid electrode, grid spacer, and an anode spacer all having circular co-extensive outside surfaces and a common hermetic seal within the confines of said metal sleeve, said metal sleeve surrounding the said circular surfaces and being spaced therefrom by said hermetic seal.

9. An electron discharge device including a base member having a cathode mounted thereon, an anode spacer, an anode mounted upon said spacer, at least one grid electrode, at least one grid spacer, and an exhaust tubulation, said grid electrode being positioned intermediate the cathode and anode by means of said base member and the grid spacer, the base member, grid electrode, grid spacer, and anode spacer having co-extensive outside surfaces and a single common seal spanning the junctures between said base member, grid electrode, grid spacer, and anode spacer, and the anode spacer and exhaust tubulation having a single common seal.

10. An electron discharge device including a base member having a cathode mounted thereon, at least one grid electrode, at least one grid spacer, an anode, an anode spacer, and an anode support member, the anode being mounted upon said anode spacer by means of the anode support member, said grid electrode being positioned intermediate the cathode and anode by means of said base member and the grid spacer, the base member, grid electrode, grid spacer, and anode spacer having co-extensive outside surfaces and a single common seal spanning the junctures between said base member, grid electrode, grid spacer, and anode spacer, and said anode spacer and anode support having a single common seal.
